UNITED STATES PATENT OFFICE.

GEORGE VIDMER, OF WASHINGTON, DISTRICT OF COLUMBIA.

GOLF PRACTICE COURT.

Application filed September 12, 1923. Serial No. 662,336.

To all whom it may concern:

Be it known that I, GEORGE VIDMER, a citizen of the United States, residing at Washington, in the District of Columbia, have invented certain new and useful Improvements in Golf Practice Courts; and I do hereby declare the following to be a full, clear, and exact description of the invention, such as will enable others skilled in the art 10 to which it appertains to make and use the same.

The present invention relates to improvements in golf practice courts in which provision is made for the safe conduct of practice shots near the initial or other tee.

An object of the invention is to provide a relatively small and compact housing in which practice shots may be indulged in with real golf clubs and balls without endangering those congregated about the tee 20 and awaiting to drive off.

The invention also contemplates the use of a housing or court in which the accuracy, distance and trajectory of the golf ball may 25 be gauged by the novice and in which the golf ball is returned to the player automatically.

It is a further object of the invention to provide an appliance of this nature for use 30 both outdoors and indoors wherein the stance and form of the player may be observed through the walls of the housing or court for the purpose of enabling a professional to correct bad form and other irregularities in the golf stance, address, etc.

With the foregoing and other objects in view the invention may be more fully described hereinafter and will be particularly pointed out in the claim appended hereto.

40 In the drawings, wherein like symbols refer to like or corresponding parts throughout the several views.

Fig. 1 is a perspective view of an improved golf practice court constructed according to the present invention;

Fig. 2 is a front elevation of the same;

Fig. 3 is a side elevation of the court;

Fig. 4 is a perspective view of a modification for indoor use; and

50 Fig. 5 is a similar view showing the skeleton frame of the court.

Referring more particularly to the drawings, A and A¹ designate rods or posts for the purpose of supporting the enclosure, and 55 guy ropes or wires B which may be stretched from the upper ends of the posts to the

ground and pegged thereto. The posts A and A¹ are disposed in pairs at the front and rear portion of the enclosure and these posts are situated apart a suitable distance to permit freedom of movement on the part of the golfer in executing his swing.

The enclosure consists of side walls C and C¹ which extend substantially from the front to the rear posts and these walls are preferably made of netting or wire mesh in order to allow flexibility should the walls be struck by the golf club or ball without doing injury thereto, and the court will be open to complete ventilation and the walls will furthermore permit the "pro" to 60 inspect the golfer from any angle and to observe any irregularities in his form or execution.

The side walls are connected by a top or roof C² of similar material and at 65 the back is a substantially vertical wall C³ which connects at its lower end with a sloping runway or chute C⁰. The sloping runway may be a continuous part with the rear wall. The various walls and roof of the 70 device are bound along the edges by binding strands H and the strands at the front and rear of the roof are continued to the posts

75 which connects at its lower end with a sloping runway or chute C⁰. The sloping runway may be a continuous part with the rear wall. The various walls and roof of the 80 device are bound along the edges by binding strands H and the strands at the front and rear of the roof are continued to the posts

85 which connects at its lower end with a sloping runway or chute C⁰. The sloping runway may be a continuous part with the rear wall. The various walls and roof of the 90 device are bound along the edges by binding strands H and the strands at the front and rear of the roof are continued to the posts

95 which connects at its lower end with a sloping runway or chute C⁰. The sloping runway may be a continuous part with the rear wall. The various walls and roof of the 100 device are bound along the edges by binding strands H and the strands at the front and rear of the roof are continued to the posts

105 which connects at its lower end with a sloping runway or chute C⁰. The sloping runway may be a continuous part with the rear wall. The various walls and roof of the 110 device are bound along the edges by binding strands H and the strands at the front and rear of the roof are continued to the posts

115 which connects at its lower end with a sloping runway or chute C⁰. The sloping runway may be a continuous part with the rear wall. The various walls and roof of the 120 device are bound along the edges by binding strands H and the strands at the front and rear of the roof are continued to the posts

125 which connects at its lower end with a sloping runway or chute C⁰. The sloping runway may be a continuous part with the rear wall. The various walls and roof of the 130 device are bound along the edges by binding strands H and the strands at the front and rear of the roof are continued to the posts

135 which connects at its lower end with a sloping runway or chute C⁰. The sloping runway may be a continuous part with the rear wall. The various walls and roof of the 140 device are bound along the edges by binding strands H and the strands at the front and rear of the roof are continued to the posts

145 which connects at its lower end with a sloping runway or chute C⁰. The sloping runway may be a continuous part with the rear wall. The various walls and roof of the 150 device are bound along the edges by binding strands H and the strands at the front and rear of the roof are continued to the posts

vas F. This vertical bar or marking is made centrally on the canvas and it is of a suitable width to receive the white golf ball and to show up the golf ball when the same is 5 driven thereagainst.

Now, the foregoing description refers to a device for outdoor use, but it is obvious that the practice of golf swings may be carried on equally well indoors and for this purpose 10 the apparatus for indoor practice will preferably take the form shown in Figs. 4 and 5 in which the mesh structure or the netting is contained within, and suspended by a preferably collapsible skeleton frame M 15 made of wood, gas pipe or other material, of small diameter or other material preferably of a tubular construction on account of lightness. The skeleton frame M consists of connected rectangular side, rear and top 20 frames and projecting above the corners of the frame are pins m to take the projecting strands h connected to the bolt ropes H of the enclosure. It will thus be apparent that for indoor use, the identical enclosure used 25 outdoors in connection with the posts may be disconnected from these posts, carried indoors and suspended from the pins m of the indoor skeleton frame. Substantially the same apparatus is thus capable of being installed 30 indoors and the same will be found particularly useful in barns, garages, gymnasiums, and club houses, although the device is also useful in private homes as the 35 space within the enclosure is not necessarily large.

In the use of the device a golfer will tee his ball at or near the front open portion of the enclosure, and facing the rear wall C³ will drive the ball into the canvas F, having 40 as his objective the marking or bar f upon the canvas. The enclosure will protect the bystanders from random blows from the golf club and will also protect those about from misdirected shots, which result in a 45 great number of injuries and not infrequently fatalities on popular golf courses. In an apparatus of this kind, the merest duffer may indulge himself in a number of practice swings at or near the starting tee 50 without endangering others, and it is the purpose of the invention to provide these enclosures in numbers about the starting and possibly other tees on golf courses where golfers, waiting to tee off, may occupy themselves profitably in improving their strokes. 55 The marking f on the canvas F will form an objective for the golfer representing sub-

stantially the flag staff and the flexible character both of the canvas F and the supporting rear wall will enable this canvas to give, 60 when the ball strikes the same, sufficiently to hold the ball for an appreciable interval of time to allow the golfer to raise his head after properly executing his follow through. The novice thereupon may obtain a correct 65 knowledge of the direction in which his ball would have taken flight and the low or high trajectory of the ball may be gauged by the height of the ball upon the elongated bar f, 70 so that the player may practice both characters of shot.

It will be noted that the device is preferably larger at the front and tapers toward the rear wall C³ and the taper may take place both as respects the side walls and the top or roof of the device. This construction permits a sufficiently large space for the activities of the golfer at the open front of the enclosure and it provides adequate 75 space at the rear for the purpose described 80 while economizing on material, and it furthermore focuses the attention of the golfer on the object marking f.

It is understood that changes in form, proportion, size and minor details may be 85 made within the scope of the claim without departing from the spirit or sacrificing any of the advantages of the present invention.

What is claimed is:—

A flexible golf practice court comprising supports having pins thereon, a netting enclosure composed of side and rear walls and a top, heavy binding strands extending along the edges of the top, said rear wall being secured to the rear ends of the side walls and the side walls adapted to be secured to the ground at their forward edges but sloping upwardly away from the ground at their rear edges, a run-way at the rear portion of the enclosure extending down from said rear wall and being secured to the sloping edges of the side walls, a flexible objective strip supported within the enclosure in forwardly spaced relation to the rear wall, loops extending from the corners of the enclosure for removably engaging said pins whereby to hold the enclosure in a distended position, and further loops at the lower portion of the rear wall for engaging certain of the supports to hold the rear wall at its lower portion away from said objective strip.

GEORGE VIDMER.
